DISPENSER

George C. Spiro, Yonkers, N. Y.

Application November 24, 1936, Serial No. 112,580

7 Claims. (Cl. 221—6)

This invention is directed to an improvement in dispensing apparatus designed particularly for the handling of granular and flaky material and constructed with a view to insuring certainty of 5 operation and simplicity and economy in manufacture.

The primary object of the present invention is to provide a dispenser of this type in which all operative parts are mounted as a unit and designed, in the preferred embodiment, to have but a single connection with the container proper, with such unit operating parts so constructed and arranged that they may be assembled exteriorly of the container and inserted therein for use in a 15 simple and convenient manner.

A further object of the invention is the use, in the preferred form, of a gate for controlling the delivery of the contents of the container, which gate is mounted for rocking movement toward and from a discharge position and held in place without the use of any connecting means, such as 20 a hinge or other support, thus materially simplifying the construction and assemblage of parts as well as reducing their cost.

25 A further object of the invention is the provision of an operating unit including a spring member placed under tension when the gate is opened and serving, when free to act, to close the gate, there being included in the operating unit an agitator which serves to agitate the contents of the container to avoid clogging and facilitate the flow of such contents through the opening when the gate is opened, the agitator being operated in 30 one direction in the opening movement of the gate and in the other direction by the spring which acts to close the gate when the opening pressure thereon is relieved.

The invention is illustrated in the accompanying drawing, in which:

40 Figure 1 is a vertical sectional view with the operating unit in elevation.

Figure 2 is a plan view of the operating unit and gate, the container being shown in transverse section.

45 Figure 3 is a broken front elevation with the gate in closed position.

Figure 4 is a broken front elevation showing the opening in the container to receive the gate.

The improved dispenser comprises a container 50 1 which, while preferably circular in cross section, may obviously be of any sectional form and any reasonable dimensions as to height and diameter. Within the container is arranged an inclined false bottom 2 which extends from the 55 lower edge of the container upwardly toward the

diametrically opposite area to provide for the gravitational feed of the material toward the outlet.

The wall of the container in vertical line with the lowest portion of the false bottom is formed with an opening 3 of appropriate width and height, the side edges 4 of which are substantially parallel and the upper edge 5 is interrupted by 5 upstanding narrow slots 6 which extend above the upper edge and have their outer edges in line with the side edges 4 of the opening.

10 A gate for controlling the opening 3 includes an outer wall 7 having a width exceeding the width of the opening 3 and a vertical dimension or length exceeding the similar or vertical dimension of the opening 3. The outer wall extends 15 beyond the upper edge of the opening 3 as an integral finger plate 8 which is inclined with respect to the outer wall or closing section 7, so that when the latter is in position to close the opening 3, the finger plate extends outwardly from the 20 wall of the container in an upward direction, as shown clearly in Figure 1 of the drawing.

25 Secured to the closure plate 7 forming a part of the gate are side plates or wings 9 which are spaced apart so that their outer surfaces bear 25 more or less snugly against the side edges 4 of the opening. The plates or wings 9 of the gate are curved on their lower edges, as at 10, to permit their swinging movement through the opening and at their upper edges are formed with 30 short lengths 11 which are at right angles to the closure plate 7, the rear edges 12 of the wings inclining downwardly and rearwardly. In applied position, the wings extend through the opening 3, the upper margins 11 extending into the narrow slots 6 at the upper edge of the opening.

35 Secured to the closure plate 7 is a bar 13 which extends rearwardly from the closure plate between the wings 9 and at a point inwardly of the gate proper is provided with a transverse bar 14 40 which serves as an agitator. A spring 15 is removably secured at one end 16 to a fixed element carried by the container wall, the opposite end of the spring being connected to or extended as a single length 17 which is looped at 18 around the 45 bar 13 immediately in advance of the agitator 14.

When the parts are in applied positions, the rear end of the spring 15 is just above the rear elevated edge of the false bottom and the spring is so tensioned that when the gate is in applied 50 position and arranged to close the opening 3, all parts will be held under the tension of the spring. In this position of the parts, it is to be particularly noted that in the preferred structure the gate proper is without hinged or other con- 55

nection with the container, as the fitting of the gate wings in the narrow slots 6 serves to guide and retain the gate in appropriate relation to the opening 3 in all positions of the gate, whether 5 closed or open, and that as the wings 9 bear against the side edges 4 of the opening 3, the gate is freely movable from opened to closed position or vice versa without possible separation of the gate from the container.

- 10 When desiring to discharge the contents of the container through the opening 3, the inclined finger plate 8 is pressed inwardly into approximate contact with the wall of the container. This swings the gate in a position indicated in 15 dotted lines in Figure 1, freeing the opening 3 for discharge of the contents moving downwardly by gravity in the container under the direction of the false bottom. During this opening movement of the gate, the spring 15 is tensioned and 20 the agitator 14 is moved forwardly. This movement of the agitator serves to break up any clods or hardened portions of the contents and insures an even, regular flow of the contents through the opening 3.
- 25 When the pressure on the finger plate 8 is relieved, the spring acts to return the gate to closed position, the closure plate 7 fully and completely closing the opening plate 3 and the agitator moving in the opposite direction to that described to 30 insure a further agitation of the contents of the container.

It is to be particularly noted that the operating unit including the spring, agitator and gate may be assembled exteriorly of the container 35 and passed through the opening 3 by appropriate manipulation, whereupon the fixing of the end 16 of the spring to the fixed element on the container, which may for example be a hook, completes the assemblage. In this connection it is 40 noted that, while the preferred form and one of the important features of the invention is the fact that the gate as a gate is without pivotal or other connection with the container, swinging on the edge formed by the meeting ends of the 45 closure plate 7 and the finger plate 8, it is nevertheless to be considered within the scope of the present invention that if desired a mounting for the gate at this point may be provided without sacrificing any of the unit details of the operating means and merely in such instance requiring 50 additional details to provide a hinged juncture. Such hinge being a conventional part of such a construction, is not particularly illustrated, and is merely referred to to indicate that within the 55 scope of the appended claims, such hinge or like connection is contemplated.

What is claimed to be new is:

1. A dispenser including a container formed with a discharge opening, a gate for controlling the flow of material through said opening, a finger plate forming an extension of the gate and operable to swing the gate to open position, the movement of the finger plate to open the gate being limited by contact of said finger plate 60 with the container, a bar extending from the gate, an agitator at one end of the bar, and a spring connected at one end to the bar in ad-

vance of the agitator and at the opposite end to the container.

2. A dispenser including a container formed with a discharge opening, a gate for controlling the passage of material through said discharge opening and including a closure plate to overlie the opening and wings extending from the closure plate inwardly of the container to define a discharge passage when the gate is opened, a finger plate extending at an angle from and formed in 10 one piece with the closure plate and movable toward the container to move the closure plate to open position with respect to the discharge opening, a spring connected at one end to the container, and means connecting the opposite 15 end of the spring to the gate, said means including an agitator movable in one direction in the opening movement of the gate under the operation of the finger plate and movable in the opposite direction under closing movement of the 20 gate under the influence of the spring.

3. A dispenser including a container formed with a discharge opening, a gate wholly free of connection with the container and movable to control the flow of material through said discharge opening, and a spring connected at one end to the container and through the opposite end to the gate, said spring serving as the sole 25 medium to maintain the gate in movable relation with respect to the discharge opening.

4. A dispenser including a container formed with a discharge opening, and a unit means for controlling the flow of material through said opening, said unit means including a gate rockable on the surface of the container in operation, 35 and a spring connected at one end to the container and through the opposite end to the gate, said spring forming the sole connection of the unit to the container.

5. A construction as defined in claim 4, where- 40 in the gate includes spaced wings extending inwardly of the container and guided in slots formed in the wall of the container.

6. A dispenser including a container formed with a discharge opening and a unit means for controlling the flow of material through said opening, said unit means including a gate rockable on the surface of the container in operation, the gate including a closure plate to cover the discharge opening and an angularly related finger plate through which the gate may be rocked on the juncture of the finger plate and closure plate, and a spring connected at one end to the container and through the opposite end to the gate, said spring forming the sole connection of 50 the unit to the container.

7. A dispenser including a container formed with a discharge opening and a unit means for controlling the flow of material through said opening, said unit means including a gate rockable on the surface of the material in operation, a spring connected at one end to the container and at the opposite end to the gate, and an agitator movable through the material in the movement of the gate, said spring forming the sole 60 connection of the unit to the container.
